UNITED STATES PATENT OFFICE.

THOMAS C. WHISLER, OF REDONDO BEACH, CALIFORNIA.

EARTH-BOARING TOOL.

Application filed May 28, 1925. Serial No. 33,363.

My invention relates to earth boring tools, and more particularly to a combination tool in which it is possible to bore a hole in an earth stratum by means of one member associated with said tool, and ream out or cave in the remaining portion of said hole by means of other members associated with said tool.

It is therefore an object of my invention 10 to provide a novel form of earth boring tool in which a body member is adapted to be detachably associated with the drill pipe or tubing of an oil or other well, which body member has associated therewith side members 15 positioned in spaced relation with said body member, there being rotary cutting elements positioned in said spaces said cutting elements being also mounted in offset relation, and adapted to be rotated not only on 20 their own axes, but also with respect to the axis of the body member, an additional guide or cutting element in the shape of a fish tail bit, core extractor, or other cutting or guiding elements, being detachably positioned 25 between said first named cutting elements.

The earth boring tools heretofore proposed, especially those of the disc bit type, have given considerable trouble in practice, 30 said discs being equipped with but single shear pins. Moreover, said discs in practice soon lose their circular shape, becoming flattened, and hence in a short time become ineffective to do the work required.

It may also be stated, that in the disc bits 35 of the known type, no provision is made for cutting away the earth formation between said discs. In hard earth formations especially, the earth sections between the discs build up rapidly, and said earth must 40 therefore either be washed away by the circulating fluid, or broken down by the weight of the drill pipe before the cutting edges of the discs can again come in contact with the bottom of the hole. By the use of my invention 45 all these objectionable features are entirely eliminated.

It is also an object of my invention to provide a novel form of device which is simple in character, easy and inexpensive to construct, durable, not easy to get out of order, and which will thoroughly and reliably effect the objects intended.

Further objects and advantages of my invention will become more apparent as the 55 description thereof proceeds.

Reference is had to the accompanying

drawings, in which similar reference characters denote similar parts. In the drawings,

Fig. 1 is a part cross sectional and part 60 elevational view showing the application of my invention to an earth stratum.

Fig. 2 is a part bottom plan and part cross 65 sectional view of my invention taken on the line 2—2, Fig. 1, looking in the direction of the arrows,

Fig. 3 is a cross sectional view on the line 70 3—3 of Fig. 2, looking in the direction of the arrows,

Fig. 4 is a side elevational view of a conventional form of fish tail bit adapted to be 75 used with my invention, and

Fig. 5 is an elevational view of a core 80 extractor which is adapted to be used alternatively with my invention.

Describing my invention more in detail, it is my purpose to provide a novel form of tool in which it is possible to cut away the inner section of an earth stratum built up when, for example a set of disc bits are 85 employed, said inner earth section being cut away in advance of said discs. This feature of my invention has a two-fold purpose: first, it prevents an accumulation of earth between the discs; secondly it also undermines and caves in that portion of the formation left to be cut away by the discs. Moreover, the entire tool assembly, including the cutting elements and drill pipe is 90 properly guided within the hole cut and tends to prevent any wobbling of said assembly, and consequently insures that a better and straighter hole is cut.

As shown in the drawings, the body member B is equipped with a screw-threaded portion 1, adapting said body member to be 95 detachably associated with the drill pipe or tubing of an oil or other well, said body member being bored as indicated by the numeral 11 to permit the passage of the circulating fluid.

The body member B is equipped with a pair of wing side members 2, preferably, though not necessarily, formed by cutting away portions of the body member B, as 100 shown, though said members may be associated with said body member in any manner found desirable, either integral therewith or secured thereto as preferred.

The lower portion of the body member B 11 is equipped with an extension 3 shaped to form a pair of cylindrical offset portions

4 and 5, as shown more particularly in Fig. 2, the shape of said offset portions, as well as the material out of which they are constructed, being any preferred. Securely connecting the extension 3 and the side members 2, is a pin *p*, of any preferred shape, one end 6 being square, hexagonal, or any other desired shape, and the portion 7, preferably, though not necessarily, cylindrical in form.

Attention is directed to the fact that the pins *p* are preferably not threaded, but are held in place by the collar of the fish tail bit F, shown more particularly in Fig. 4, or the core extractor C, shown in Fig. 5, or any plug, guide, or guiding member that may be used instead. As will be manifest, said pins are held in double shear, providing an extremely rigid construction, and thus effectually obviating the single shear feature which has caused so much trouble in the disc bits heretofore proposed.

Securely mounted on the pins *p* are flanged bushings 8, shaped internally to conform to the configuration of the end 6 of said pins. On said bushings the cutting elements or discs 9 are mounted, said discs being positioned within the spaces 10, and are of course in offset relation, as distinctly shown in Fig. 2. The fish tail bit F, or the core extractor C, or whatever other cutting tool or guide may be used in lieu thereof, is screwed into the extension 3, as shown.

When the body member B is rotated in a clockwise direction, the cutting elements 9 will cut away the earth stratum, but will leave a central or intermediate earth section, which section continually accumulates between said cutting elements, and must in some way be removed, either by means of a circulating fluid, introduced into the hollow portion 11 of the body member B, or broken down by the weight of the drill pipe before the cutting edges of the elements 9 again come in contact with the bottom of the hole.

This section of the earth building up between the elements 9 also tends to prevent said elements from rotating on their own axes, resulting, as hereinbefore stated, in causing said elements soon to become flattened, and accordingly ineffective to do their work.

To obviate these objectionable features, an intermediate guiding or cutting device must be introduced between the elements 9, or a set of such elements may be used. As hereinbefore explained, said additional device or devices, cut or bore a hole in the earth stratum in advance of the elements 9, and consequently said elements 9 function merely to ream out said hole and cause the earth bored by said device to cave in.

When a core extractor is used with my novel form of device, said extractor not only functions to take the core but reams the hole

as well, thereby reducing the time of taking a core to a marked extent, since in most of the ordinary processes of extracting cores from an earth formation it is necessary to make an extra trip into the hole with the reamer, and numerous sections of drill pipe, to ream that portion not taken out by the core extractor.

In operation, as the body member B is rotated in a clockwise direction, the cutting elements 9, being offset, give a clearance between the following edge of said elements, and the side of the hole cut. It will thus be clear that the leading edge of each cutting element cuts at a longer radius than the distance between the following edge of said cutting elements and the common axis thereof.

It will of course be understood that I do not desire to be limited in practice to the particular type of cutting elements used, nor to their number, so long as one or more of said cutting elements be positioned on said tool in advance of the others.

While I have thus described my invention with great particularity, it will be obvious that the same may be modified throughout a wide range. I therefore do not propose to be limited to the exact details of construction shown and described but reserve the right in practice to make any and all modifications thereof that fall within the scope of the appended claims.

I claim as my invention:

1. In an earth boring tool, in combination, a body member, means on said body member for securing the same to a drill tubing, said body member being provided with a pair of vertical cut away portions, a horizontal pin detachably mounted in each side of said body member insertable from within said body member and extending across each of said vertical cut away portions, a rotary cutting element positioned in each of said cut away portions, and adapted to be rotated on said pins, said cutting elements being positioned in offset relation, and an additional cutting device positioned on said body member in advance of said cutting elements and directly holding said pins in position.

2. In an earth boring tool, in combination, a body member adapted to be detachably associated with the drill tubing of an oil or other well, wing side members associated with said body member, said side members being spaced from said body member, said body member being equipped with a hollowed out portion, a pin detachably mounted in each of said side members and insertable therein from within said body member, a flanged bushing positioned in each of said spaces, and mounted on each of said pins, a rotary cutting element mounted on said bushings, said cutting elements being positioned in offset relation and an additional

cutting device detachably associated with said body member, said additional cutting device directly holding said pins in position.

3. In an earth boring tool, in combination, 5 a hollowed out and internally screw-threaded body member, a pair of side members positioned in spaced relation with said body member, a fixed element connecting each of said side members to said body member, a 10 cutting element on each of said fixed elements, and adapted for rotation thereon, and an additional cutting device screw-threaded into said body member and positioned between said rotary cutting elements and 15 adapted to prevent said fixed elements from emerging from the tool when it is operated.

4. An earth boring tool equipped with a hollowed out body member screw-threaded internally for receiving and holding a cutting tool, a pair of side members positioned in spaced relation with said body member, a pair of cylindrical members extending across the entire length of each side of said body member and in offset relation with each 20 other, a pin insertable from within said body member and adapted to extend through openings in said body member and said side

members, a rotary cutting element positioned on each of said pins, and adapted to engage with a planed surface on each of said cylindrical members, whereby the shearing stresses on said pins will be balanced, and an additional cutting device screw threaded to said hollowed out body member to hold said pins 30 in position.

5. An earth boring tool comprising, in combination a hollowed out and internally threaded body member, a pair of pins insertable from within said body member and extending externally through spaces in said 40 body member, means on said pins for preventing the rotation thereof, cutting members positioned on each of said pins and adapted to be rotated thereon, said cutting elements being positioned in off set relation, 45 an additional cutting tool detachably associated with said internal threaded body member, and means on said last named tool for directly holding said pins in position so that they may not be removed while said tool 50 is being operated.

In testimony whereof I have signed my name to this specification.

THOMAS C. WHISLER.
